UNITED STATES PATENT OFFICE.

JOHN PETRI, OF ELBERTA, ALABAMA.

PORTABLE FENCE.

1,102,075.

Specification of Letters Patent. Patented June 30, 1914.

Application filed March 18, 1914. Serial No. 825,650.

To all whom it may concern:

Be it known that I, JOHN PETRI, a subject of the King of Hungary, residing at Elberta, in the county of Baldwin and State of Alabama, have invented certain new and useful Improvements in Portable Fences, of which the following is a specification.

This invention relates to certain new and useful improvements in portable fences.

10 The primary object of the device is to provide a fence structure that is easy and cheap to manufacture and at the same time is adapted for readily changing its position from one course or direction to another.

15 A further object is to provide a portable fence post having a plurality of line wires secured thereto and adapted for hooking engagement with the adjacent post and also supplied with a shiftable brace member fold-

20 able within the post body.

A still further object is to provide a fence structure consisting of a plurality of posts, each of which carries the requisite fence line wires and braces and each post being capable of individually maintaining its normal supporting position in the assembled fence structure.

With these general objects in view and others that will appear as the nature of the 20 invention is better understood, the same consists in the novel combination and arrangement of parts hereinafter fully described, illustrated in the accompanying drawings, and pointed out in the appended claims.

35 In the drawings forming a part of this application and in which like designating characters refer to corresponding parts throughout the several views: Figure 1 is a front elevation of a portion of a fence embodying my invention. Fig. 2 is a top plan view thereof. Fig. 3 is a perspective view of the pivoting end of the fence brace with the pivot pin. Fig. 4 is a detail perspective view of a portion of a post having a brace 40 secured therein, and, Fig. 5 is a similar view with one of the side portions of the post broken away.

Referring more in detail to the drawings, it is designed to employ a plurality of posts 50 10 formed with anchoring bases 11 and whereby the posts may be positioned at any desired place in a field and be normally maintained in an upright position. The present post is preferably formed of U-bars 55 or channel-bars fixedly mounted in the bases 11, which latter may be made from metal,

cement, or any other desired material. Each of the posts 10 has a plurality of line wires 12 attached to one corner thereof, preferably by tying the same through corner perforations 13 while said wires so secured to the posts are of equal length, being sufficient to have their free ends engage hook members 14 carried by the adjacent face of the next succeeding post employed in the fence construction. Brace struts 15 are 60 adapted for spanning and bracing two adjacent posts and are provided with central longitudinal slots 16 for receiving the pin 17 which spans the space between the side 65 flanges of the post. By this structure it will be evident that each post has secured thereto the requisite number of line wires 12, the free ends of which are engaged with the hooks 14 of the next succeeding post, 70 while the brace 15 of the post is adapted 75 for an arcuate swinging movement downwardly in contact between the two posts and thereby sufficiently stretching the line wires to impart stability to the structure. It is 80 evident that when positioned for use as shown in Fig. 1, the brace 15 may be moved forwardly upon its pivot 17 and within the space 18 of the carrying post and then allowed to drop vertically and centrally 85 within the post space 18 until the slotted end of the brace rests upon the post base 11, and whereby it will be apparent that a compact structure is provided for a portable 90 fence member. It will also be seen that the lower corner 19 of the brace when positioned horizontally as best shown in Fig. 5, is 95 squared for engaging the rear web of the post and thereby positioning the brace horizontally and preventing its further downward pivotal movement while the opposite or upper corner 20 of said brace end is rounded sufficiently to allow clearance when the brace is upwardly pivoted for assuming its closed or knocked down position. 100

For dis-assembling, the brace 15 of each post is foldable within its carrying post, which thereby releases the tension upon the line wires, and these are then readily unhooked from the adjacent post and wound 105 around the carrying post with its strut inclosed therein.

While the forms of the invention herein shown and described are what are believed to be preferable embodiments thereof, it is 110 nevertheless to be understood that various forms and modifications thereof may be had

without departing from the spirit and scope of the invention as claimed.

What I claim as new and desire to secure by Letters Patent is:—

- 5 1. A fence structure comprising a channel-bar post, a weighted base for said post, a slotted brace slidably-pivoted within the channel of said post, one edge of a flange of said post provided with perforations, line 10 wires secured through said perforations, and hook-wire engaging means carried by the web portion of said post.
- 15 2. A fence structure comprising channel-shaped posts, weighted bases upon said posts, transverse pins extending through the channels of said posts, braces having closed longitudinal slots therein adapted for pivotally receiving said pins, said posts provided with perforations, a plurality of 20 line wires secured in said perforations, hooks carried by said posts at points thereon opposite to said perforations, and adapted for engaging the free ends of said line wires, said wires and braces being of lengths

substantially equal to the normal distances 25 between two adjacent posts when assembled in a fence structure.

3. A portable fence structure comprising a base, a channel bar mounted thereon and having perforations through a flange thereof, line wires fixed in said perforations, a pin secured between the side flanges of said bar and spanning the channel thereof, a brace strut being slotted for substantially one-half of its length and having its slotted 30 end provided with one angular corner and the opposite corner rounded, the slot of said strut adapted for receiving said pin with the strut slideable within the channel of said bar and further adapted for horizontally 35 positioning with said angular corner engaging the rear web of the bar.

In testimony whereof I affix my signature in presence of two witnesses.

JOHN PETRI.
